US00D942945S

(12) **United States Design Patent** (10) **Patent No.:** **US D942,945 S**
(45) **Date of Patent:** **** Feb. 8, 2022**

(54) **WIRELESS MOBILE PHONE CHARGER FOR VEHICLE**

(71) Applicant: **LG ELECTRONICS INC.**, Seoul (KR)

(72) Inventor: **Sangmin Park**, Seoul (KR)

(73) Assignee: **LG ELECTRONICS INC.**, Seoul (KR)

(**) Term: **15 Years**

(21) Appl. No.: **35/509,156**

(22) Filed: **Oct. 23, 2019**

(80) **Hague Agreement Data**

Int. Filing Date: **Oct. 23, 2019**

Int. Reg. No.: **DM/206752**

Int. Reg. Date: **Oct. 23, 2019**

Int. Reg. Pub. Date: **Apr. 24, 2020**

(30) **Foreign Application Priority Data**

Apr. 29, 2019 (KR) 30-2019-0020161

(57) **CLAIM**

The ornamental design for a wireless mobile phone charger for vehicle, as shown and described.

DESCRIPTION

1. Wireless mobile phone charger for vehicle

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

1.15 : Another perspective view shown in an environment. In **1.1** through **1.14** the broken lines are for the purpose of illustrating portions of the wireless mobile phone charger for vehicle that forms no part of the claimed design. In **1.15** the broken lines are intended to show environment only and forms no part of the claimed design; the reproduction **1.1** to **1.7** are indicating before change; the reproductions **1.8** to **1.14** are after change for adjusting angle of charger pad; reproduction **1.15** is a perspective view showing a state of use.

1 Claim, 15 Drawing Sheets
